UNITED STATES PATENT OFFICE

ALBERT J. GURNEY, OF CANTON, OHIO, ASSIGNOR TO THE AMERICAN MINE DOOR COMPANY, OF CANTON, OHIO, A CORPORATION OF OHIO

ROCK DUSTER

Application filed November 15, 1927. Serial No. 233,407.

The invention relates to apparatus for spraying or spreading rock dust or the like in mine tunnels and similar places in order to cover or mix with the coal dust which ordinarily is deposited upon the floor, walls and ceiling of such tunnels, for the purpose of preventing explosion of this coal dust.

The object of the improvement is to provide an apparatus which may be carried upon a car or the like adapted to be moved in the tunnel, and the apparatus may comprise a hopper and a power driven feed mechanism for conveying powdered limestone or the like from the hopper to a blower which blows the rock dust from a nozzle, or hose, spraying the same upon the ceiling and walls of the tunnel and permitting a part of the dust to fall upon the floor thereof, thus covering or mixing with the coal dust which is deposited upon the walls and floor of the tunnel.

The above and other objects may be attained by constructing the apparatus in the manner illustrated in the accompanying drawings, in which

Figure 1 is a perspective view of the improved apparatus looking toward the forward end thereof;

Fig. 2, a perspective view of the interior of the improved machine showing the hopper and feed mechanism;

Fig. 3, a longitudinal sectional view of the feed end of the hopper and feed mechanism showing the blower and nozzle;

Fig. 4, a transverse sectional view through the hopper and feed mechanism;

Fig. 5, a side elevation of the nozzle and hose connection, showing the means for operating the valve therein;

Fig. 6, a plan sectional view through the U-shaped housing as on the line 6-6, Fig. 3; and

Fig. 7, a plan sectional view as on the line 7-7, Fig. 3 showing the U-shaped housing.

Similar numerals refer to similar parts throughout the drawings.

The apparatus is designed to be moved through a mine tunnel and the like, and may be arranged to be conveyed upon a railroad track, by a locomotive or the like, and for this purpose may comprise the frame 1 upon

which are mounted the journal boxes 2 in which the axles 3 are journaled.

Flanged wheels 5 may be mounted upon the axles and may be adjustably secured thereon and spaced as by the spacing collars 55 6 in order to accommodate the same to various gauges of track. These flanged wheels are adapted to run upon rails such as indicated at 7.

A coupling device, as shown at 8, may be provided upon each end of the frame, for the purpose of connecting the apparatus to a locomotive, and also for connecting one or more cars behind the apparatus, whereby an additional supply of rock dust may be 65 carried into the mine.

A hopper may be built upon the frame comprising the front and rear end walls 9 and 10 respectively and the inwardly inclined side walls 11. This hopper may be filled 70 with powdered limestone or the like and is provided with a conveyer mechanism for feeding this rock dust to the blower and nozzle and hose connection to be hereinafter described.

For the purpose of carrying the powdered rock dust forwardly, through the bottom of the hopper, and feeding it to the fan, and nozzle, and hose connection, a pair of conveyer screws 12 may be located in parallel 80 relation in the bottom of the hopper.

A baffle plate 13 may be provided over the exit ends of the conveyer screws, and a sliding valve 14 is arranged to simultaneously control the discharge of dust from both conveyer screws. When the valve 14 is entirely closed, the rock dust fed forwardly by the conveyer screws will be permitted to circulate between the screws, passing backward 85 between the screws and beneath the baffle plate 13, thus relieving pressure upon the closed valve and preventing the material from being wedged against the valve and being forced through the same, around the 90 screws.

This valve may be connected, as by the link 15 with an operating lever 16, extending through the outside of the front wall of the hopper, and provided with a handle 16a lo- 100

cated in position to be conveniently reached for operation.

As best shown in Fig. 4, each of the conveyer screws may be located in a trough 17, in the bottom of the hopper, whereby the rock dust will be fed downward from each of the inclined side walls 11 to the adjacent trough.

For the purpose of preventing the rock dust from packing or caking in the bottom of the hopper, and in order to assist the conveyer screws in feeding the dust forward in the hopper, an agitating device may be provided.

This agitator may comprise the shaft 18 located slightly above the conveyer screws and parallel with and equally spaced from said conveyers. Inclined pins or fingers 19 are provided upon said agitator shaft for continually agitating the rock dust. This agitator shaft is preferably continuously rotated in the opposite direction to that of the conveyer screws.

The screw 20 of each conveyer shaft terminates at the forward end of the hopper, while the shaft is continued through the opening 21, controlled by the valve 14, and extends into a substantially U-shaped housing having the head portion 22 which communicates with both of the openings 21 and the leg portions 23, one of the conveyer screws being extended into each of said leg portions, and having a bearing at the forward end of said housing as indicated at 24.

Forward of the head portion of this U-shaped housing each conveyer shaft may be provided with a short screw 25 and angular propeller blades 26 for the purpose of feeding the rock dust backward to the crosshead 22.

With this construction it has been found by actual practice that a plug of the rock dust may be always kept in this crosshead to feed into the fan chamber 27, thus preventing back pressure from the fan from forcing the rock dust backward into the hopper.

Each portion 23 communicates transversely with the fan chamber 27 and as the material is fed forward by the conveyer screws to this point, the angular propeller blades 26 convey the material transversely into the fan chamber. As the material passes into the fan chamber, it is brought immediately into the path of the air and is carried out through the discharge end of the fan chamber.

This fan chamber 27 is mounted in front of the hopper and contains the rotary fan 28 arranged to be driven as by the motor 29. The fan chamber discharges into a forked or bifurcated connection 30 having one branch 31 extending upward and slightly forward to which is attached a nozzle 32 which may be of the general design shown in Figs. 1 and 3.

This nozzle, as illustrated in these figures

of the drawings, is provided with the arcuate mouth 33, arranged to be constricted at its central portion by the bolt 33^a, so arranged that a fan-shaped spray of the rock dust may be delivered from the nozzle to the walls and ceiling of the tunnel, a certain portion of the dust, of course, dropping upon the floor of the tunnel, thus covering or mixing with the coal dust sufficiently to prevent explosion of the same.

By constricting the mouth of the nozzle at its central portion, the rock dust will be discharged substantially uniformly from all parts of the mouth. It will be evident that the blast of air from the blower will naturally issue from the central portion of the nozzle mouth, and if this central portion of the mouth is the same width as the end portions, very little of the dust would be blown from the ends of the mouth upon the side walls of the tunnel. The bolt 33^a may be operated to adjust the center of the mouth in accordance with the air blast.

The second branch 34 of the bifurcated connection extends forwardly of the nozzle and a hose 34^a may be connected to the same to convey the rock dust to any point away from the apparatus, being particularly adapted for spraying holes in the walls and ceiling of the tunnel.

For spraying rock dust in a tunnel leading off at an angle from the one in which the apparatus may be located, a large hose may be substituted for the nozzle 32, upon the branch 31 of the connection.

For the purpose of blowing the rock dust through either one of the passages 31 or 34, a valve 35 may be located in the bifurcated connection and arranged to shut off either branch thereof as shown in full lines and dotted lines in Fig. 3. In order to make this valve airtight, a flexible binding 35^a may be provided around its edges.

For the purpose of operating the valve 35, a lever 60 may be fixed upon the outer end of the shaft 61 of the valve. This lever may have the handle portion 62 and the opposite end portion 63, pivotally connected to a rod 64 which is slidably located through the pivoted bracket 65.

A spring 66 may be interposed between this pivoted bracket and the head 67 of the rod, whereby as the handle is moved toward either position the spring will throw the lever over center to the limit of its movement, thus securely holding the valve in either position to which it is moved.

Any suitable power means (not shown) may be provided for driving the screw conveyers 12 and the agitator shaft 18, and any suitable gearing (not shown) may be interposed between the motor, screw conveyers, and agitator shaft, for continuously rotating the agitator shaft in one direction and both of the conveyer screws 130

in a direction opposite to the rotation of the agitator shaft as shown by the arrows in Fig. 4. Thus, the rock dust is prevented from packing or caking in the bottom of the hopper, and the agitator cooperates with and assists the conveyer screws in uniformly feeding material forward in the hopper to the blower. Referring to Figs. 3, 6 and 7 of the drawings, the conveyers 12 terminate at points located at each side of the periphery of the blower 27, there being a transverse communication between the end portion of each conveyer and the periphery of the blower.

I claim:

1. Conveyor blower apparatus including a hopper, longitudinal troughs in the bottom of the hopper, a blower communicating with the hopper, a discharge connection communicating with the blower, conveyer screws located in said troughs for feeding material from the hopper to the blower whereby the material will be blown from the discharge connection, an agitator shaft in the hopper located in a plane between the conveyer screws, and means for continuously rotating the agitator shaft in one direction and both the conveyer screws in a direction opposite to the rotation of the agitator shaft.

2. Conveyor blower apparatus including a hopper adapted to contain rock dust, a transverse passage communicating with the hopper, a blower communicating with the central portion of said transverse passage, and conveyer screws in the hopper terminating at the end portions of the transverse passage, whereby rock dust is fed by the screws from the hopper to the transverse passage and packed therein to prevent back pressure from the blower from blowing the rock dust back into the hopper.

3. Conveyor blower apparatus including a hopper, a blower communicating with the hopper, a pair of spaced, parallel conveyer screws in the bottom of the hopper, for conveying dust from the hopper to the blower, a slide valve between the hopper and the blower, and a baffle plate over the discharge ends of the conveyer screws, whereby, when the valve is closed, the dust carried forward by the conveyer screws will circulate backward beneath the baffle plate and between the screws.

4. Conveyor blower apparatus including a hopper adapted to contain rock dust, a substantially U-shaped casing communicating with the hopper, a blower communicating with the central portion of the U-shaped casing, a pair of conveyer shafts in the hopper having their forward ends extended into the legs of said U-shaped casing, screws upon the shafts terminating at the forward ends of the hopper, and propeller blades upon the forward ends of the shafts for feeding dust backward in the legs of the U-shaped casing.

5. Conveyor blower apparatus including a

blower, a conveyer located at each side of the periphery of the blower and a transverse communication between the end portion of each conveyer and the periphery of the blower.

6. Conveyor blower apparatus including a blower, a conveyer located at each side of the periphery of the blower, a transverse communication between the end portion of each conveyer and the periphery of the blower and means for feeding material transversely through said communications from the conveyers to the blower.

7. Conveyor blower apparatus including a fan casing, a fan within the casing, a pair of parallel conveyer housings, one located upon each side of the fan casing, and a screw conveyer in each housing, the end portion of each housing communicating transversely with the fan casing.

8. Conveyor blower apparatus including a fan casing, a fan within the casing, a pair of parallel conveyer housings, one located upon each side of the fan casing, a screw conveyer in each housing, the end portion of each housing communicating transversely with the fan casing and means in each housing for conveying material through the transverse communication into the fan chamber.

In testimony that I claim the above, I have hereunto subscribed my name.

ALBERT J. GURNEY.
